FIG. 3.

FIG. 4.

FIG. 5.

Inventor
Harry M. Robertson
By
Geo. M. Miller
Attorney

UNITED STATES PATENT OFFICE.

HARRY M. ROBERTSON, OF CLEVELAND, OHIO.

KILN.

Application filed January 28, 1928. Serial No. 250,294.

This invention relates to tunnel kilns in which material is passed continuously through a zone of heat capable of calcining, firing or otherwise treating material or articles in large quantities.

One object of the invention is to provide a novel kiln structure in which the residue, such as dust, ashes and/or cinders, due to combustion of pulverized coal and like fuel or other form of fuel instead of passing into the area occupied by the material treated, will be collected or caused to settle out of the path of the fire and subsequently to be removed at the convenience of the operator.

10 This removal may be accomplished without interrupting or in any way interfering with the continuous operation of the kiln.

Another object of my invention is in providing facilities for access to the combustion chamber for whatever purpose may be desired. Among such purposes may be noted the inspection of the operation of the firing; that is, whether the combustion is taking place in the manner intended. Also it may be desired under some circumstances to supply fresh air to the combustion chambers independently of the fuel ports. Access to these combustion spaces at a point beneath the zone of combustion is also important in the proper care of the spaces and the removal of dust, ashes and the like.

Other objects of my invention will be evident from the following description taken in connection with the accompanying drawings illustrating my preferred embodiment of the invention. On these drawings,

Fig. 1 is a horizontal longitudinal section, on the line 1—1 of Fig. 2, of a portion of a kiln embodying my invention;

Fig. 2 is a vertical longitudinal section on the line 2—2 of Fig. 1;

Fig. 3 is a vertical cross section on the line 3—3 of Fig. 1;

Fig. 4 is a vertical cross section on the line 4—4 of Fig. 1; and

Fig. 5 is a vertical cross section on the line 5—5 of Fig. 1.

As illustrated in the drawings I have shown a portion of a tunnel kiln of generally conventional type so far as its main structure is concerned and in which my improvements have been embodied, such kiln in the present embodiment comprising a heating zone A, a preheating zone B and a cooling zone C, only portions of the zones B and C being shown. The base or foundation 6 may be of any suit-

able material, but as illustrated it is preferably of monolithic concrete. Longitudinally through the center of the zones B, A and C are mounted the rails 7 of a track along which, in successive order, trucks carrying the material to be treated can be conveyed. The foundation 6 supports on each side a series of vertical metal I-beams 8, connected at their upper ends by transverse tie rods 9. By this means the outer walls 10, of the kiln are held in proper position. These walls 10 may be of masonry, brick or concrete.

An inner wall 11—11 extends parallel to each of the outer walls 10—10 and spaced from the latter. Suitable heat insulating filling 12—12 occupies the spaces between the inner and outer walls. The inner walls are made of material similar to that of the outer walls. Bridging the space between the top of the inner walls 11—11 and the corresponding portions of the outer walls a suitable plate or other cap 13 is provided. Inwardly of the plates 13 are pediments 14—14 which support in turn the ends of the roof arch 15. The entire top of the kiln within the outer walls 10—10 is covered with a suitable heat insulating filling 16.

Ledges 17—17 rise vertically from the base within the heating zone A and extend from end to end thereof. These ledges 17 are also formed of masonry or other suitable material and spaced from the inner walls 11—11, to support vertical partitions of open brick or checker-work 18 through which the heat passes. Opposite each wall of brickwork 18 and in spaced relation thereto is a fireback 19 mounted against the walls 11—11 to protect the latter from the high temperatures obtained. Across the top extending from the brickwork 18 to the adjacent fireback 19 is a top partition 20 having vertical baffles 21 suitably spaced longitudinally of the zone A, as shown in Fig. 2.

The above general features of the kiln are in the main similar to those shown in my prior Patents No. 1,610,968, granted Dec. 14, 1926, and No. 1,621,222, granted March 15, 1927, to which reference is made for further details regarding the general construction and operation of such apparatus.

As shown in Fig. 1, the firing or heating zone A of the kiln is recessed at each end by re-entrant walls forming bays 22—22, which extend inwardly close to the passageway through the kiln leaving only enough clearance for the customary trucks. As illus-

trated in Fig. 3, each bay is defined by spaced transverse walls 10', an inner wall 11', and by a roof slab 23, the wall 11' being in the same plane with the checkerwork 18 so that the 5 bay will extend inwardly beyond the plane of the adjacent combustion chamber 24 and a settling or collecting chamber 26.

Referring again to Figs. 1 and 5 it will be seen that at either side of the space for the 10 material (a) a combustion chamber 24 is formed by the fireback 19, checkerwork 18 and slab 20, above the level of series of fuel ports or fire boxes; and (b) the spacing of the 15 ledge 17 from the fireback 19 and wall 11 forms the settling or collecting chamber 26 extending from end to end of the heating zone and in communication throughout its length with the adjacent combustion chamber 24 and each of the fuel ports or fire boxes 25, 20 so that the products of combustion flow from the fuel ports through the upper portion of the settling chamber to the combustion chamber. As the settling chamber is directly below the combustion chamber, all the residue inci- 25 dent to combustion will fall thereinto, instead of passing outwardly through the checker-work 18. The combustion chambers 24 extend on each side of the line of travel of the material for the full distance of the heating 30 zone and have a bay 22 at each end thereof.

As shown by way of example this combustion chamber is served by four fuel ports 25. These ports may be adapted for the burning of pulverized fuel but other fuel may 35 be used as desired.

At the ends of the settling chambers, the inner side walls 10' of the bays are pierced to provide clean-out ports or passageways 27.

It will be noted that these ports are on the 40 level of the settling chamber 26 and beneath the combustion chamber 24. These ports are shown as inwardly flaring (Fig. 1), and by preference, the inner surfaces of the ledges 17 are inclined outwardly so that the bottoms 45 of the chambers 26 are in line with the ports 27.

It will be evident that the inlet ports 25 will admit streams of gaseous or pulverized fuel mixtures in sufficient quantity to establish an area of intense heat within the combustion chambers 24, from which the hot gases pass through the brickwork 18 into the area occupied by the trucks carried on the rails 7-7. Suitable means (not illustrated) 50 are provided for venting the products of combustion or for causing them to flow toward one end of the kiln. However, it is not feasible to allow any solid particles, dust, ashes or other residue that may occur as products 55 of combustion to travel in this course and the settling chambers 26 beneath the chambers 24 serve the purpose of entraining such materials and holding the same as a deposit.

By providing at each end of each settling 60 chamber 26, a suitable clean-out port 27 it is

a matter of ease to remove these deposits therefrom as fast as they accumulate. This may be done in any of a number of ways as will occur to those skilled in this industry, for example a blast of steam, air or the like from 70 a nozzle may be directed in the port 27 at one end of either chamber 26 and the accumulated materials thus driven out through the opposite clean-out port 27. As there is but one collecting chamber 26 for each series of fire 75 boxes and this chamber is co-extensive with the adjacent combustion chamber and open at its opposite ends, all of the accumulated residue may be cleaned out at one operation, at 80 will. Again the nozzle of a vacuum hose line may be passed in a port 27 and the material drawn out of the chamber 26 directly. In either event the operation of the kiln is not interfered with.

Numerous changes in proportion and minor details may be made within the scope of this invention and without departing from the sense of the claims.

What I claim is:

1. In a tunnel kiln, a longitudinally extending combustion chamber, a fuel port, a settling chamber connecting said fuel port with the combustion chamber, and a clean-out port at one end of said settling chamber.

2. In a tunnel kiln, a combustion chamber extending throughout a portion of the kiln, a longitudinal series of fuel ports, a settling chamber common to said ports and connecting them with said combustion chamber, and a clean-out port at one end of said settling chamber.

3. In a tunnel kiln, a combustion chamber extending throughout a portion of the kiln, a longitudinal series of fuel ports, a settling chamber common to said ports and connecting them with said combustion chamber, and a clean-out port at each end of said settling chamber.

4. In a tunnel kiln, a combustion chamber, a fuel port beneath said combustion chamber, a settling chamber connecting the fuel port with the combustion chamber, and a clean-out port at one end of said settling chamber.

5. In a tunnel kiln, a combustion chamber, a longitudinal series of fuel ports, a settling chamber common to said ports and connecting them with said combustion chamber, and a clean-out port at one end of said settling chamber beneath the level of the combustion chamber.

6. In a tunnel kiln, a combustion chamber longitudinally along one side of said kiln, a settling chamber beneath and coextensive with said combustion chamber, a series of fuel ports leading into said settling chamber, and a clean-out port opening into each end of the settling chamber.

7. In a tunnel kiln, a combustion chamber longitudinally along one side of said kiln, a settling chamber beneath and coextensive

with said combustion chamber, a series of fuel ports leading into said settling chamber, and a clean-out port opening into each end of the settling chamber on the level of the fuel ports.

8. In a tunnel kiln having side walls forming a heating zone, bays in one of said side walls at the ends of said zone, a combustion chamber within said side wall extending between said bays, and a clean-out port opening inwardly from each bay into the area beneath said combustion chamber.

9. In a tunnel kiln having side walls forming a heating zone, bays in one of said side walls at the ends of said zone, a combustion chamber within said side wall extending between said bays, a settling chamber beneath

said combustion chamber, and a clean-out port opening inwardly from each bay into the settling chamber.

20

10. In a tunnel kiln having side walls forming a heating zone, re-entrant walls at the ends thereof forming bays at each end of said zone, a longitudinal series of fuel ports in each side wall, a common combustion chamber for each series of ports extending between said bays, settling chambers connecting the fuel ports with the combustion chambers and a clean-out port opening inwardly from each bay into the settling chambers at the level of the fuel ports.

In testimony whereof I affix my signature.

HARRY M. ROBERTSON.
